Primary Examiner—Louis S. Zarfas*Assistant Examiner*—Gregory Andoll*Attorney, Agent, or Firm*—Marshall A. Lerner; Marvin H. Kleinberg; Kleinberg & Lerner LLP[57] CLAIM

The ornamental design for a shoe upper, as shown and described.

DESCRIPTION

FIG. 2 is a perspective showing rear, right and top thereof;

FIG. 3 is a left side elevational view thereof;

FIG. 4 is a right side elevational view thereof;

FIG. 5 is a top plan view thereof;

FIG. 6 is a front elevational view thereof; and,

FIG. 7 is a rear elevational view.
